JOHN ELBRIDGE HARNER, OF DODGE CITY, KANSAS.

CHILD'S TOY.

Application filed February 9, 1927. Serial No. 166,974.

The invention relates to wheeled toys for children and provides an article which may be propelled by the weight of the child and the swaying of the body to shift the weight, 5 the swaying of the body being rhythmical and so timed as to develop intermittent impulses for propelling the device.

The invention contemplates a drive wheel which is eccentrically mounted and caused 10 to rotate under the weight of the rider and a shifting of the weight by a to and fro swaying movement of the body.

The invention provides a toy representative of a flying machine and mounted upon 15 wheels, the rider sitting astraddle of the toy and swaying the body in substantially the same manner as when mounted upon a hobby horse.

While the drawings illustrate a preferred 20 embodiment of the invention, it is to be understood that in adapting the means to meet specific needs and requirements, the design may be varied and such other changes in the minor details of construction may be resorted to within the scope of the invention 25 as claimed, without departing from the spirit thereof.

For a full understanding of the invention and the merits thereof, reference is to be had 30 to the following description and the drawings hereto attached, in which,—

Figure 1 is a side view of a toy embodying the invention.

Figure 2 is a top plan view thereof.

Figure 3 is a vertical, central, longitudinal sectional view of the drawing.

Figure 4 is a vertical, transverse sectional view on the line 4—4 of Figure 3, looking 40 towards the front, as designated by the arrows.

Figure 5 is a detail view showing the manner of attaching a grooved pulley to its stem and the flexible steering element to the pulley.

Corresponding and like parts are referred 45 to in the following description and designated in the several views of the drawings by like reference characters.

The body of the toy has the general outline 50 of a flying machine of the monoplane type, and is equipped with centrally disposed wheels 1, a front wheel 2 and a rear wheel 3. The rear portion of the body 4 tapers rearwardly and is provided with a rudder 5 and side wings 6. A propeller 7 is located at the front of the body 4 and side

wings 8 project laterally from opposite sides of the body adjacent the front. These wings 8 provide rests for the feet of the rider. A seat 9 is located at the top of the body midway between the ends thereof and is in line with the axis of the wheels 1, thereby admitting of the weight of the rider being disposed directly above the wheels 1 so that a swaying of the body to and fro shifts the weight and imparts a rocking movement to the body 4. The wheels 1 are intended, primarily, to carry the load. An axle 10 receives the wheels 1 and is secured to the body 4 in any determinate way and projects laterally therefrom a uniform distance, whereby to space the wheels 1 so as to support the toy in upright position. The body of the toy comprises spaced side pieces and an intermediate filler, the several parts being constructed in any determinate way. The rear wheel 3 is mounted in a frame 11 having a stem 12 which is mounted in the body to turn freely and receive a limited vertical movement. An open helical spring 13 is mounted upon the stem 12 between the frame 11 and body 4 and operates as a buffer. A grooved pulley 14 is fast to the stem 12 and receives a flexible element 15 which admits of steering. A post 16 is vertically mounted in the front portion of the body 4 and its stem receives a grooved pulley 17 which is fast thereto, said pulley receiving the flexible element 15. A handle bar 18 is applied to the upper end of the post 16. 50 The grooved pulleys applied to the stems of the frame 11 and post 16 serve as means to retain such parts in place. The flexible element 15 preferably consists of an endless wire which is crossed intermediate the front and rear grooved pulleys and this element is made fast to the respective grooved pulleys by means of a screw 19 which likewise enters the stem upon which the pulley is mounted and secures said pulley thereto.

The front wheel 2 constitutes the driver and its axle 20 is eccentric to the circumference of the wheel, and in consequence peripheral portions of the wheel are disposed at different distances from the center or axis 105 of the wheel. Advantage is taken of this arrangement to utilize the weight of the child or other occupant of the vehicle as means for propelling the toy. Moreover, by having the wheel 2 eccentrically mounted the toy receives a propelling movement as the weight of the rider is shifted by a swaying

of the body to and fro. This swaying of the body must be timed to the position of the wheel 2 and when the major axis of the wheel 2 is disposed forwardly of the axle 5 20, a forward shifting of the weight results in a downward movement of the front end of the body 4 of the toy, and a rotation of the wheel 2 to simultaneously advance the toy, and while the wheel 2 is regaining an 10 operative position the toy moves forwardly under the impulse imparted thereto and the rider at the same time imparts a rearward swaying movement to the body. After a little practice the swaying of the body becomes 15 mechanical and automatically times itself to the position of the wheel 2 so that when the body is moved forwardly the front portion of the body 4 of the toy descends under the weight of the rider and rotates the wheel 2 in a direction to propel the toy forwardly. In order that the major axis of the drive wheel 2 may normally occupy a position off center, so that a forward movement of the toy is assured when the rider leans 20 forward, a weight 21 is applied thereto. This is effected by boring a hole through the wheel and plugging it with lead which may be applied thereto in a molten state, or in any preferred way. 25 The rudder 5 is preferably applied to the upper end of the steering post or stem 12, so as to move therewith and add to the interest of the toy. The wings 8 constitute parts of a plate or board which is notched 30 in its rear edge at a medial point to clear the drive wheel 2. The side pieces comprising

the body 4 are extended, as indicated at 22, to receive the axle 20 and are notched to receive the rear edge of the wings 8 and thereby insure a substantial connection. 40

Having thus described the invention, I claim:

1. A toy comprising an elongated body, centrally disposed wheels, a front wheel and a rear wheel, the rear wheel being supported 45 in a frame having a pivotally mounted stem adapted to receive a limited vertical movement, a front post, pulleys secured to the stems of the post and rear wheel frame, and a flexible connection between the pulleys of 50 the posts and rear wheel frame to admit of a turning of the latter for steering.

2. A toy comprising an elongated body, supporting wheels intermediate the ends of the body, a front wheel eccentrically mounted and constituting the driver, a rear steering wheel yieldably mounted, a front post, 55 grooved pulleys applied to the stems of said posts and the rear wheel frame and an endless flexible element connecting the grooved 60 pulleys whereby to transmit movement from the post to the rear wheel for steering.

3. A toy comprising an elongated body, supporting wheels intermediate the ends of the body, a front wheel eccentrically mounted and constituting the driver, a rear steering wheel, a front post, and a connection between the front post and the steering wheel 65 whereby to transmit motion from the front post to the rear wheel for steering. 70

In testimony whereof I affix my signature.
JOHN ELBRIDGE HARNER. [L. S.]
